AGITATOR

Filed Aug. 15, 1929

UNITED STATES PATENT OFFICE

SAMUEL H. GIBSON, OF LAKEWOOD, OHIO, ASSIGNOR TO THE FANNER MANUFACTURING COMPANY, OF CLEVELAND, OHIO, A CORPORATION OF OHIO

AGITATOR

Application filed August 15, 1929. Serial No. 386,198.

This invention relates to agitating devices, and more particularly to agitators of the collapsible type, such as are used in containers for mixing or stirring the contents.

An object of this invention is to provide an improved form of agitator which can be manufactured at very low cost.

Another object of this invention is to provide an agitator of the collapsible type in which means is provided for maintaining the agitator paddle in position for most efficient operation.

Other objects and advantages of this invention will be apparent from the following description taken in connection with the accompanying drawings in which:

Fig. 1 is a side elevational view, partly in section, showing the agitator of my invention in operative position within a container;

Fig. 2 is a fragmentary sectional view showing the manner in which my agitator is inserted into a container;

Fig. 3 is a sectional view taken on line 3—3 of Fig. 1;

Fig. 4 is an elevational view, partly in section, showing the sleeve used in the container opening; and

Fig. 5 is a fragmentary elevational view showing another manner of supporting the agitator.

Referring now to the drawings in detail, in Fig. 1 I show a container 10 in which the agitating device of my invention has been mounted. The container 10 is shown, in this instance, as a bilge barrel, but the form of container in which my agitator is adapted to be used is not an essential feature of the invention. Such containers are invariably provided with a threaded opening 11 at the center of one of their end walls or heads, and it is through this opening that my agitator is inserted and operated.

The agitator, as shown in the drawings, comprises a shaft 12 which, in this instance, is square in cross-sectional shape, a paddle 13 connected to the shaft adjacent one end thereof, and a sleeve for maintaining the shaft and paddle in position for efficient operation. For connecting the paddle to the shaft, I provide the socket member 14 which

receives one end of the shaft 12 and is secured thereto by means of the pin 15. The lower end of the socket member is shaped to provide a flat, offset portion 16 to which the paddle is secured by means of the pivot pin 17. The paddle blades 15' are inclined or twisted so that, in form, the paddle resembles a screw propeller. In mounting the paddle on the socket member, the pivot pin 17 is made to pass through the center of the paddle 13 so that, although the paddle is rotatable upon this pivot pin, it will always be in a balanced condition, that is to say, in stable equilibrium.

For supporting the paddle and maintaining the same in position for efficient operation, I provide an elongated bushing or sleeve 19 which is screwed into the threaded opening 11 with the elongated portion 19' extending into the container and loosely surrounding the agitator shaft. This sleeve is provided with a recess 20 in its upper end into which the square agitator shaft extends. The bottom of this recess forms a shoulder 21 upon which the paddle and shaft are suspended by means of the washer 22 and the pin 23. A crank 24 is provided for turning the agitator shaft and paddle. This crank is provided with a handle 25 and a shank 26 having a socket 27 which receives the end of the square agitator shaft when the shank is inserted in the recess of the sleeve 19. The sleeve 19 serves as a bearing for the agitator shaft, preventing wobbling of the paddle 13, and maintaining the agitator in proper alignment with the axis of the container regardless of the position in which the container may be.

To insert the agitator into the container, the paddle 13 is rotated upon its pivot pin to lie along the shaft 12 in an inoperative position, as shown in Fig. 2. With the paddle in this inoperative position, the agitator is inserted through the opening 11 and lowered into the container. When the lower end of the paddle 13 strikes the bottom wall of the container, the paddle rotates about its pivot pin from the inoperative position, and assumes the operative position shown in Fig. 1, adjacent the bottom wall of the container. Before inserting the paddle into the contain-

er, the sleeve 19 is slipped onto the shaft, after which the washer 22 is placed on the shaft and the pin 23 is driven through the shaft. After the paddle has been lowered into position in the container, the sleeve is screwed into place in the threaded opening 11, thus holding the paddle in suspended position just above the bottom wall of the container.

If desired, the agitator may be supported upon the bottom wall of the container rather than suspended from the top wall as shown in Fig. 1. This arrangement is illustrated in Fig. 5, which shows the socket member 14' provided with an extending tip 28 which is received in the recess of the bearing plug 29 screwed into the bottom wall of the container. In this arrangement, the washer 22 and pin 23 which are used in the suspended form are omitted, and the loose connection between the agitator shaft and the sleeve permits longitudinal movement of the shaft, so that the agitator will always assume a position with the tip 28 in contact with the bottom wall of the container, thereby always positioning the paddle close to the bottom surface of the container, where it will effectively stir up deposited sediment. With this arrangement, bulging of the end walls or heads of the container does not materially affect the alignment or positioning of the paddle for efficient operation.

The upper end of the shaft, which extends into the sleeve, preferably terminates below the threaded part 30 of the recess 20 so that a plug 31 may be screwed into the sleeve to form a closure for the container when the crank 24 is removed and the agitator is not being used, thus permitting the agitator to be retained in the container during shipment.

Upon rotation of the shaft and the paddle 13 by means of the crank 24, the propeller shape of the paddle causes a positive movement of the contents of the container which insures a thorough mixing and kneading.

It will now be apparent that I have provided a very simple form of agitator which can be quickly and easily inserted in folded form through the opening of a container, and unfolded within the container by contact of the agitator with the wall of the container. The agitator of my invention can be manufactured at low cost, and can be installed in a container without the need of special tools or exercise of unusual skill.

While I have disclosed the preferred embodiment of my invention, I do not intend to limit myself to the exact details shown and described, but regard my invention as including such modifications and changes as come within the scope of the appended claim.

Having thus described my invention, I claim:

In an agitator of the type to be inserted through a container opening, the combination of a shaft, a paddle having a central

portion with blades extending laterally therefrom in opposite directions, a single means for maintaining said shaft in alignment with the axis of said container comprising an elongated sleeve extending into the container around said shaft and having one end thereof secured in said opening, and means connecting said shaft and said paddle whereby the latter is movable from a position substantially parallel to said shaft to a position at substantially right angles to said shaft, said connecting means comprising a member having a socket portion adapted to receive the lower end of said shaft and an integral flattened portion to which the central portion of said paddle is pivoted.

In testimony whereof, I hereunto affix my signature.

SAMUEL H. GIBSON.
